Patented Mar. 12, 1918.

UNITED STATES PATENT OFFICE.

JESSE M. SHORT, OF JOPLIN, MISSOURI.

DRILLING-MACHINE.

1,258,952.

Specification of Letters Patent.

Patented Mar. 12, 1918.

Application filed December 21, 1917. Serial No. 208,306.

To all whom it may concern:

Be it known that I, JESSE M. SHORT, a citizen of the United States, residing at Joplin, in the county of Jasper and State 5 of Missouri, have invented certain new and useful Improvements in Drilling-Machines, of which the following is a specification.

My invention relates to drilling machines, to drill wells, mines, and the like, and has 10 particular reference to the provision of shock absorbing means, for connecting the flexible element of the apparatus, such as a rope, cable or the like, with the walking beam.

15 An important object of the invention is to provide means of the above mentioned character, which are simple in construction, strong, durable, and reliable in operation.

Other objects and advantages of the invention will be apparent during the course 20 of the following description.

In the accompanying drawings forming a part of this specification and in which like numerals are employed to designate like 25 parts throughout the same,

Figure 1 is a side elevation of a machine embodying my invention.

Fig. 2 is an end elevation of the supplemental walking beam, and,

30 Fig. 3 is a detail section taken on line 3—3 of Fig. 2.

In the drawings, wherein for the purpose of illustration is shown a preferred embodiment of my invention, the numeral 5 designates a base, upon which is secured a vertical support or upright 6. The numeral 7 designates a main walking beam, preferably formed of a pair of spaced I-beams 8, having blocks 9 and 10 arranged between the same, at the ends thereof. These blocks are rigidly secured to the I-beams by bolts 11. The block 9 is provided with an opening to receive a pivot element or shaft 12, carried by the support or upright 6.

45 Arranged to operate or slide between the I-beams 8 of the walking beam 7, is a cross head 13, having pivotal connection with a pin 14, carried by a crank 15, rigidly secured to a shaft 16. This shaft is journaled through the upper end of a stationary support or upright 17, secured to the base 5. The shaft 16 receives its rotation from a pulley 18, which may be driven by any suitable means. It is obvious that when the 50 pulley 18 is rotated, the walking beam 7

will be oscillated in a substantially vertical plane.

Arranged rearwardly of and near the support or upright 6 is a vertical support or upright 19, rigidly attached to the base 5 by any suitable means. Pivoted to the support 19 is a spool or drum 20, adapted to have a flexible element 21 wound thereon. This flexible element may be a rope, cable or the like. The flexible element 21 passes 65 about a grooved pulley 22, pivoted to the upper end of a beam or mast 23. A drilling tool 24 is secured to the free end of the flexible element 21.

The numeral 25 designates a supplemental walking beam, arranged above the main walking beam 7 and extending longitudinally thereof. The supplemental walking beam is of approximately the same length as the main walking beam, and preferably 70 extends from the forward end of the main walking beam to a point near and spaced from the rear end of such main walking beam. The supplemental walking beam 25 has a knuckle 26, which is rigidly secured 75 to its rear edge, at the rear end thereof, the supplemental walking beam preferably being in the form of an I-beam. The upper knuckle 26 has pivotal connection, at 27, with a lower knuckle or knuckles 28, arranged upon opposite sides of the upper I-beam 8, and rigidly secured thereto, by means of bolts or the like. The knuckle or knuckles 28 are arranged near and spaced from the rear end of the main walking 80 beam 7, and positioned wholly upon the forward side of its pivot 12.

At its forward end, the supplemental walking beam 25 has a preferably flat transverse plate 29, arranged therebeneath and 95 rigidly secured thereto by means of bolt 30 or the like. Arranged upon the upper edge of the upper beam 8, at the forward end thereof, is a preferably flat transverse plate 31, rigidly secured thereto by means of bolts 32 or the like. Disposed above the supplemental walking beam 25, and free from direct connection therewith, is a preferably flat transverse plate 33, as shown. The plates 29, 31 and 33 are provided near their 100 ends with aligned openings 34, for slidably receiving rods 35, provided at their lower ends with heads 36, and having their upper ends screw-threaded to receive adjusting nuts 37. Surrounding the rods 35, between 110

2
 the plates 29 and 31, are compressible coil springs 38, while compressible coil springs 39 surround these rods between the plates 29 and 33. Particular attention is called to 5 the fact that the springs 39 are heavier or stiffer than the springs 38, while the nuts 37 may be employed to regulate or alter the tension of these springs. Rigidly secured to the supplemental walking beam 25, near its 10 forward end, and rearwardly of the springs 38 and 39, are straps or bars 40, having pivotal connection with a sheave wheel or pulley 41, having the flexible element or cable 21 passed therebeneath.

15 The operation of the machine is as follows:

The rotation of the pulley 18, by means of the intermediate elements, causes the main walking beam 7 to oscillate in a substantially vertical plane. This oscillatory movement is imparted to the supplemental walking beam 25, through the medium of the yielding connection between the forward ends of these elements. It is thus apparent 20 that the yielding connection will absorb the shocks transmitted to the flexible element 21, without lessening the force or blow of the tool or bit 24. The heavier springs 39 enable the supplemental walking beam 25 to 25 quickly raise the tool or bit 24, while the lighter springs 38 serve to catch the slack in the flexible element 21. By this means it is found that the life of the cable 21 or the like is greatly prolonged, and often doubled, 30 thereby effecting a substantial saving in the 35 cost of operating the machine.

It is to be understood that the form of my invention herewith shown and described is to be taken as a preferred example of the 40 same, and that various changes in the shape, size, and arrangement of parts may be resorted to without departing from the spirit of the invention or the scope of the subjoined claims.

45 Having thus described my invention, I claim:

1. In a machine of the character described, a main pivoted walking beam, a supplemen-

tal walking beam extending longitudinally of the main walking beam and having its 50 rear end pivoted to the main walking beam near the rear end of such main walking beam, yielding means connecting the forward ends of the two walking beams, means to oscillate the main walking beam, and a 55 wheel connected with the forward portion of the supplemental walking beam and adapted for engagement with a flexible element.

2. In a machine of the character described, 60 a main pivoted walking beam, a supplemental walking beam extending longitudinally thereof and pivotally connected with the same, yielding means serving to connect corresponding ends of the main walking beam and supplemental walking beam, means to oscillate the main walking beam, and a wheel carried by the supplemental walking beam and adapted for engagement 65 with a flexible element. 70

3. In a machine of the character described, a main pivoted walking beam, a supplemental walking beam arranged above the same and extending longitudinally thereof, means to pivotally connect the corresponding end 75 portions of the two walking beams, an element secured to the opposite end of the main walking beam, an element secured to the corresponding end of the supplemental walking beam, a rod connected with the first named 80 element and having slid able engagement with the second named element and provided at its upper end with a stop, a spring surrounding the rod and disposed between the first and second named elements, and a 85 spring surrounding the rod and disposed between the second named element and the stop, the second named spring being stiffer than the first named spring.

In testimony whereof I affix my signature 90 in the presence of two witnesses.

JESSE M. SHORT.
